UNITED STATES PATENT OFFICE.

GEORGE ALLEN MULLEN, OF WOODBURY, NEW JERSEY.

SYSTEM OF LIGHTNING-CONDUCTORS.

1,244,118.

Specification of Letters Patent. Patented Oct. 23, 1917.

Application filed November 6, 1915. Serial No. 59,957.

To all whom it may concern:

Be it known that I, GEORGE ALLEN MULLEN, a citizen of the United States, residing at Woodbury, in the county of Gloucester 5 and State of New Jersey, have invented certain new and useful Improvements in Systems of Lightning-Conductors; and I do hereby declare the following to be a full, clear, and exact description of the invention, 10 such as will enable others skilled in the art to which it appertains to make and use the same.

My invention relates to lightning conductors.

15 The object of my invention is to provide a system of lightning conductors which shall approximately form a metallic cage surrounding the structure.

In carrying out my invention, I make use 20 of the ridge rolls, ridge cappings, flashings, and rain spouts that form a part of the structure to be protected from lightning. I make use of these parts when they are formed of non-corrosive metal, or if said 25 parts are very heavy, I make use of them even if they are formed of corrosive metal. Should any of these parts not be suitable for use in my system of lightning conductors, or should it be necessary to provide protection 30 at any part of the structure where said parts do not exist, I make use of a composite conductor preferably of ribbon form.

Said ribbon conductor is formed with a 35 core, preferably of non-corrosive metal and to said core I apply a plurality of metallic coatings to prevent corrosion and side flashing.

Wherever the word conductor is used, it 40 is to be understood as meaning an electric conductor of any cross section, and whether imbricated, woven, twisted or solid.

I provide each vertical conductor with a 45 separate ground and join all vertical conductors together by a conductor laid below the surface of the earth.

I furthermore connect with my system of 50 lightning conductors all steam pipes, water pipes and all other metallic pipes, excepting gas pipes and all large masses of metal which form a part of the structure to be protected.

In the drawings:—

Figure 1, is a perspective view of the 55 structure provided with my improved system of lightning conductors, the windows

and doors being omitted for the sake of clearness;

Fig. 2, is a perspective view of the connector with which I join two sections of my ribbon conductor; 60

Fig. 3, is a perspective view of a discharge point and support such as I apply to ridge rolls and ridge cappings;

Fig. 4, is a view of a portion of the rain conductor, showing the manner of attaching 65 a ground thereto;

Fig. 5, is a perspective view of a stable provided with my improved system of lightning conductors, the doors and windows being omitted for the sake of clearness; 70

Fig. 6, is a view of my improved non-inductive ground shown as buried below the surface of the earth and surrounded with a hygroscopic conducting packing;

Fig. 7, is a perspective view of a portion 75 of my conducting ribbon, showing the perforation in same and the method of attaching same to the structure to be protected;

Fig. 8, is a plan view showing the method 80 of applying discharge points and conductors to a pair of chimney pots; and

Fig. 9, is a detail view showing the application 85 of my improved system of lightning conductors to a pair of chimney pots.

In the drawings:—

10 represents a structure provided with a ridge roll or ridge capping 11 along the ridge of the roof and with the ridge rolls or ridge cappings 12—12 along the top of the gables 13—13. 90

To the ridge rolls or ridge cappings 11 and 12—12, I apply any suitable number of discharge points 14—14—14. The discharge points 14 are applied to a support 15 provided with holes 16—16, which support is 95 secured to the structure by screws 17—17—17, which pass through the holes 16—16 in the support 15. A stud such as 18 is riveted to each support 15 and the discharge point 14 is placed upon the stud 18 and secured 100 thereto by rolling the depressions 19 in the lower portion of the discharge point 14, the inside of said depressions fitting in grooves provided in the stud 18.

Wherever there is a chimney pot or chimney opening to be protected, I place ribbon conductors such as 20—20 across the openings 21—21 of the pot or chimney and secure to said conductors 20—20 a third conductor 22 by rivets such as 23—23, and on the con- 105
110

ductor 22 midway between the chimney pots, I apply the discharge point 24. The discharge point 24 is in all respects similar to the discharge point 14, shown in Fig. 3, and is secured to a stud similar to 18, the lower portion of said stud also serving to secure the conductor 25 to the conductor 22. The ends of the conductors 20 and 22 are bent down around the bead of the chimney pots 10 as shown at 26-26 and 27-27 respectively in Fig. 9.

The ridge rolls 11 and 12 are connected together by ribbon conductors 28-28 and said conductors are further connected to the 15 flashings such as 29-29, the lower ends of which are connected by the ribbon conductors 30-30-30-30 to the rain trough sections 31-31-31.

The rain trough sections, by their construction, are usually in electrical connection with the rain conductors 32-32-32-32, or if not in electrical connection therewith, I provide an electrical connection between the trough 31 and the conductors 32.

25 To the lower end of each rain conductor 32, I apply a clamp 33 formed of metallic ribbon which fits snugly around the rain conductor 32. The clamp 33 is provided with ears such as 34 and between said ears, 30 the end 35 of a ground 36 is secured by the rivet or bolt 37.

Flashings 38-38-38-38 are connected with the ridge rolls 12-12. Should the flashings 38 not form a part of the structure 35 to be protected, or should they be of light, corrosive material, I use my improved metallic ribbon in place of the flashings 38. In some cases, I use my improved metallic ribbon along any exposed edge of the structure 40 to be protected as at 42 along the edge of the roof 43.

I preferably attach my improved metallic ribbon, shown at 39 in Fig. 7, by means of screws such as 40, or in lieu thereof by nails, 45 passing through slots such as 41. The screw or nail is applied through the center of the slot 41 so that expansion or contraction of the ribbon 39 due to changes of temperature will not produce an undue stress on said 50 screws or nails.

To connect two portions on my improved ribbon conductor, I make use of the connector 44. This connector consists of a body 45 of the same width and thickness as my improved ribbon conductor. The body 45 terminates at each end with two ears 46-46 and 47-47 each of the same width and same thickness as the body 45. Slots 48-48 are provided between the ears 46 and 47, said 55 slots being of a width equal to the thickness of my improved conductor ribbon. Holes 49-49 are provided through the ears 46-46 and 47-47. The end of the ribbon conductor is provided with a hole adapted to 60 register with one of the holes 49, when

said conductor is introduced within one of the slots 48. Rivets or bolts shown at 50-50 are placed through the holes 49 to secure the conductors 39 and the connector 44 together. The juncture of the ribbon and connector is then to be securely soldered. 70

Wherever a juncture is made between a ridge roll and ribbon, between a flashing and ridge roll, between a flashing and conductor, between a conductor and a rain trough, or 75 between a rain conductor and a ground, said juncture is preferably riveted and soldered.

Referring to Figs. 1 and 6, it will be noted that my non-inductive ground 36 is formed of my improved conductor ribbon and consists of a plurality of coils 51 wound in one direction and formed integrally with a plurality of coils 52 wound in the opposite direction. The object of winding the coils 51 and 52 in opposite directions is to eliminate 80 self induction, while obtaining the increased surface afforded by a long length of ribbon.

The ground 36 is introduced into a hole provided in the earth 53 and a packing such as 54 is packed around the ground 36. The 90 packing 54 may extend to the surface of the earth, as shown in Fig. 6, or it may extend to just above the coils 51 and the rest of the hole be filled up with earth.

The packing 54 is preferably composed of 95 a substance which is a fairly good conductor of electricity, such as powdered coke, charcoal or carbon, and in order to insure that the same shall be continuously moist, I mix with said coke, charcoal or carbon, some 100 salt such as chlorid of sodium or potassium hydroxid, which is highly hygroscopic.

The grounds 36-36-36-36 are connected together by a conductor such as 55 buried below the surface of the earth. The conductor 55 extends entirely around the structure connecting all grounds together. 105

Wherever any of the metal which forms part of my system of lightning conductors approaches a large mass of metal, other than 110 gas pipes, which forms a part of the structure to be protected, the said metal is connected to said mass as is shown in Fig. 1, where the rain conductor 32 on the extreme left of the structure is connected by the ribbon 56 to the water pipe 57. I preferably make such a connection which acts in conjunction with the protection afforded by the plurality of coatings given to my ribbon conductor to prevent side flashing. 115

Fig. 5, shows a stable provided with ridge rolls 58-58 having the discharge points 59-59 and connected by the ribbon conductors 60-60 with grounds not shown; said grounds being connected together by a 120 ribbon conductor below the surface of the earth similar to 55, in Fig. 1.

The ventilator 61 of the stable is protected by the discharge point 62 applied to the ridge roll 63 thereof, which is connected by 130

the conductor 64—64 with the ridge rolls 58—58.

The hay track 65 in the loft of the stable is connected by the conductor 66 with one of 5 the ridge rolls 58, or with both of said ridge rolls, in order to prevent side flashing; this being additional protection to the protection afforded against side flashing by the plurality of metallic coatings applied to my 10 conductor ribbon.

When ridge rolls, ridge cappings, flashings, rain troughs or rain conductors do not exist, or when if they do exist they are unsuitable for use as lightning conductors, I 15 use my improved form of ribbon conductor in lieu of such parts.

I have stated that all joints are riveted and soldered. Joints above ground may be so

secured or they may be secured by welding, but all joints below ground I preferably secure by welding. 20

I claim:—

1. The combination of a plurality of uninsulated conductors forming a cage about a structure comprising internal metallic 25 masses with grounds connected to said conductors, and connections between said conductors and said metallic masses.

2. The combination with a plurality of chimney openings of a metallic grid across 30 each opening, a bar connecting said grids and a discharge point mounted on said bar and a ground connected to said bar.

In testimony whereof, I affix my signature.

GEORGE ALLEN MULLEN.
